UNITED STATES PATENT OFFICE.

JAMES DUNN MACLAY, OF LOUISVILLE, KENTUCKY; MINNIE H. MACLAY
ADMINISTRATRIX OF SAID JAMES DUNN MACLAY, DECEASED.

AMALGAMATOR.

SPECIFICATION forming part of Letters Patent No. 614,965, dated November 29, 1898.

Application filed October 26, 1897. Serial No. 656,437. (No model.)

To all whom it may concern:

Be it known that I, JAMES DUNN MACLAY, a citizen of the United States, residing at Louisville, in the county of Jefferson and State of Kentucky, have invented certain new and useful Improvements in Amalgamators, of which the following is a specification.

My invention relates to that class of amalgamators shown in United States Patent to 10 Calder and Maclay, dated October 4, 1887, No. 371,031.

My present invention is an improvement upon the former one in particulars hereinafter described and claimed.

15 In the accompanying drawings, three sheets, Figure 1 is a perspective view of my improved amalgamator. Fig. 2 is a vertical longitudinal section thereof. Fig. 3 is a vertical transverse section of the same. Figs. 4 and 5 are 20 detail views of the flour or float gold arrester.

A is an open framework, comprising a base A', vertical posts or standards A² A² A² A², suitably braced and connected by transverse and longitudinal cross-pieces, as shown.

25 B is the ore-feed block, cast or formed in a single piece and provided with a vertical oblong or elliptical opening B' therethrough for the down-passage of the gold-bearing material or slush therethrough. The lower longitudinal edges of this opening B are rounded, as shown at b', and the upper end of the opening is made flaring, as at b², for the ready entrance of the material from any suitable feed or supply pipe. The ore-feed block is rigidly 30 suspended transversely in the middle portion of the frame A by means of four rods or bolts b b b b, the upper ends of which are secured to the stationary transverse frame-bar A³.

C is the vertically-adjustable oscillating 35 box, suspended by means of the A-shaped box, suspended by means of the A-shaped hangers C', which straddle the bar A³ and are connected at their upper ends to a rock-shaft C², having knife-edges resting on bearing-plates C³ upon the upper edges of the top 40 longitudinal frame-bars A⁴; but these hangers may be otherwise pivotally supported at their upper ends. The lower ends of the hangers C' are provided with longitudinal slots c c, and the box is provided with L-shaped straps c' c', the upper ends of which project above 45 the box and are provided with transverse

bolts c² c², which pass through the slots c c and are provided with nuts for clamping the parts in their adjusted positions. It will be readily seen that the hangers could be provided with other means for adjusting the height of the box relative to the block B without departing from the scope of my invention.

The middle of the box C is provided with a mercury-receptacle C⁴, formed by transverse end pieces C⁵ C⁵ and a bottom plate C⁶, between which and the bottom of box C is formed an open-ended passage C⁷. The working faces of both plate C⁶ and block B are flat 65 and smooth. The end pieces C⁵ C⁵ are provided above their lower edges with slots or openings c⁵ c⁵, at the outer sides of which are troughs or boxes c⁴ c⁴, which may be connected by a short pipe or passage with the interior of said receptacle C⁴. The rear end of 70 the box C is closed and its forward or discharge end is open for the exit of the waste material.

D is what I term a "flour or float gold arrester," and it consists of a frame or network of silver or copper, and when placed in the opening or bore B' of block B will separate and subdivide the descending column of gold-bearing material or slush as it rapidly 80 descends. This framework D is kept clean and polished by the waste mercury contained in the milled ore being treated.

The receptacle C is filled to about the level of the lower ends of its openings c⁵ with mercury, and it is adjusted so as to bring its bottom close up to the bottom face of the block B, and motion is imparted to the box C by any suitable means—such, for instance, as crank-shaft E and pitman F. As the stream 90 of ore and water containing the float and flour gold rush into the ore-slot it strikes and dashes from one part of the frame D to another till it meets the main body of mercury, and undergoes another rubbing and scouring 95 and polishing between the block B and bottom plate C⁶, when it becomes amalgamated. The mercury that keeps the frame or network D in order is, as before stated, the waste from milled ore, so in a manner the floured 100 mercury by dashing and tumbling down the opening or slot B' and striking from part to

part of the frame D brings a quantity of floured mercury to unite again and is caught and keeps the frame in good order, so that there is little or no chance of any gold escaping after coming in contact with the main body of mercury.

In the drawings I have shown the frame D as formed of a vertical bar d and a series of transverse vertically-apertured bars d' , the two being connected by interlocking mortises d^2 . At the juncture of the bars oblique apertures d^3 are formed through both, which lead from one side of the vertical bar to the other, so that the circulation of the ore-slush will be facilitated. The bars d' decrease in length from the middle bar toward both end bars.

It will be seen that I do away with all the wheels and rollers of the patented machine referred to and that the swinging motion of the box C is more easily effected. The adjustment of the flat bottom plate C⁶ to the flat lower face of block B may be so close that the two faces will scour, grind, and polish, and free refractory ore (from the finest milled ores even if milled to eighty meshes to the inch) from the oxids and all foreign matter. The small arc required by the oscillating motion, say three inches for full stroke, enables the finest ore milled to be sucked in and scoured. Should it be attempted to adjust the faces of the block and plate in the patented machine so close together, the mercury resists all attempts of the ore to pass therebetween in paying quantities.

In this improved machine it has been demonstrated by practice and test and commercial use that the ore and mercury will pass between the bottom portions of the block B and receptacle C when the latter is oscillated in a manner or to a degree which was not practicable with the patented machine. This is mainly due to the oscillation of the receptacle C, whereby the ore and mercury are caused to run down a straight incline at each movement of the receptacle in either direction. Thus gravity directly aids mechanical agitation, and a new and superior result is produced.

The fine adjustment of the working faces

of the block B and plate C⁶ is assisted by the lower rounded or beveled edges $b' b'$ of the former. The lighter waste material will float off through openings c^5 into troughs or boxes c^4 , from which it will overflow into the bottom of box C and eventually flow out of the open end thereof to a waste-chute. Any mercury trapped in boxes or chutes c^4 will be returned to receptacle C⁴.

What I claim is—

1. The combination, with the ore-feed block, having a vertical passage open at each end, of the float-gold arrester, comprising a frame formed of suitable metal, such as silver, and including a vertical bar and apertured transverse bars of varying lengths, oblique openings being formed through the bars at their junctures, substantially as set forth.

2. The combination of the pivotally and adjustably suspended, oscillating mercury-trough, the feeding-block therein, the lower face whereof is in close proximity to the bottom of the mercury-trough and adapted to coat therewith to rub or scour the ore, a vertical feed-passage in said block, and a frame composed of perforated bars adapted to catch the flour or float gold, in said passage.

3. The combination of the pivotally and adjustably suspended oscillating mercury-trough, the feeding-block therein, whose lower face is in close proximity to the bottom of the mercury-trough and adapted to coat therewith to rub or scour the ore, a vertical feed-passage in said block and a frame composed of substantially horizontal perforated bars adapted to operate as specified.

4. The combination with a suitable fixed frame, an ore-feed block having a vertical passage, and the float-gold arrester arranged in said passage and comprising a metal frame, of the oscillating mercury-box arranged beneath and partly inclosing such block, and adapted to coöperate with the latter, to scour and grind the ore, and hangers for said box having knife-edge supports, substantially as shown and described.

JAMES DUNN MACLAY.
